EUGEN SECKLER, OF LAKE VIEW, NEW JERSEY.

COMBER-BOARD.

1,150,396.

Specification of Letters Patent. Patented Aug. 17, 1915.

Application filed January 2, 1915. Serial No. 20.

To all whom it may concern:

Be it known that I, EUGEN SECKLER, a subject of the Emperor of Germany, residing at Lake View, in the county of Passaic, and State of New Jersey, have invented certain new and useful Improvements in Comber-Boards, of which the following is a specification.

This invention relates to comber board structures for looms and it has for its principal object to provide a comber board structure which will permit the harness cords to be quickly and readily adjusted relatively to each other, as in altering the loom for weaving fabrics varying in width or "count" of the warp.

In the accompanying drawings, Figure 1 is a front elevation of a Jacquard machine, the harness cords depending therefrom, a fragment of the batten structure of a loom and two of the improved comber board structures as they are preferably employed; Fig. 2 is a plan view of the improved comber board structure; Figs. 3 and 4 are a transverse sectional view on the line $x-x$ in Fig. 2 and a fragmentary longitudinal sectional view of the improved comber board; Fig. 5 illustrates a detail; and Fig. 6 is a diagrammatic view illustrative of the adjustment of one of the harness cords.

The holes to guide the harness cords A shown in Figs. 1 and 6 are formed in the improved comber board structure by two crossed groups of parallel horizontal rods a and b (Fig. 2), the group a being arranged in practice to extend transversely and the group b approximately longitudinally of the warp.

The rod group a may be supported as follows: c is a suitable elongated rectangular frame including the cross bars d each formed with a rabbet d' on the inside. In this rabbet there is removably secured, by means of screws e , a strip f which is perforated 45 to receive the end portions of the rods of the group a , which are kept against undue longitudinal movement by abutting against the shoulder formed by the rabbet d' of the cross bar, as shown best in Fig. 4. At a suitable distance apart there are provided the cross strips g penetrated by the rods of the group a and serving to keep said rods properly spaced from each other; said strips also serve as intermediate supports for the rods a to keep the latter from sagging, and to this end the strips g rest at their ends on the

angular bars g' which are supported at their ends on the cross-bars d and at the middle by the stirrups g'' secured to the sides c' of the frame. It is preferable that the rods a be staggered, as shown in Fig. 3. It is obvious that in order to change the number of the rods a or replace them with new ones from time to time it is only necessary to detach one or the other of the strips f .

For supporting the rod group b and providing for the adjustment thereof I preferably employ the following instrumentalities: The long sides c' of the frame c have inwardly facing longitudinal grooves h on the inside. The inner face of each side c' has secured to it two spaced metal strips i partly covering its groove h (Fig. 3). The ends of the rods b are received in the grooves h , extending between the two strips i in each instance. For convenience in removing the group b a part c'' of each side c' overlying the groove h may be detachable, being held in place by screws c''' or otherwise.

j designates two series of wedge-shaped spacers employed for altering the spacing of the rods b . They are provided with eyes j' as shown best in Figs. 3 and 5 and are strung on the two horizontal bars k , which extend parallel with the rods a , their ends being received in vertical slots l in pairs of brackets m which are suitably secured to the sides c' of the frame c ; the bars k are adapted to be vertically adjusted by the screws n , having lock nuts o (adapted to bind against the brackets m), and then held securely by the screws p , each pair of screws n and p being tapped at the opposite ends of the slot l in each bracket. The spacers j are kept substantially upright by the sides c' of the frame and the rods or wires q arranged in the brackets m parallel with said sides (Fig. 3). The spacers alternate with the rods b , and it will be obvious that upon their vertical adjustment the spacing of the rod group b will be varied, assuming, of course, that the rods and spacers are all held in compact or contacting order. After the adjustment the rods and spacers as an entirety are held against lateral displacement by the blocks r , each of which is penetrated by a bolt r' whose T-shaped head is received in the slot h and whose nut r'' coacts with the head when screwed up tight to clamp the block to the strips i . Reserve spacers are shown at the extreme right and left on the bars k in Fig.

2; if more rods *b* were required to be used, a corresponding number of the reserve spacers would be brought between the two blocks *r* of each rod—accomplished by removing the section *c''* of each side *c'* so that the blocks can be detached in order to allow the reserve spacers to pass them.

The improved comber board is suitably supported in a horizontal plane between the 10 Jacquard machine *s* (Fig. 1) and the plane of the batten structure shown in Fig. 1 as including the batten proper *t* and the reed *u*. By raising or lowering the bars *h* the spacing of the rods of the comber board will 15 be changed to suit the "count" of the particular reed *u* employed, it being understood that after the adjustment is effected the blocks *r* are employed to hold the group of rods *b* and spacers compactly together and 20 in vertical registry with the warp. It will be seen that the rods *b* may be shifted as a group so as to stand obliquely to the length of the warp, the advantage of which is that the holes which they form for guiding the 25 harness cords will be in front or rear elevation distributed equally over the entire breadth of the cord group thereby to provide a certain clearance for each cord with respect to the others in the same front to rear row which would not exist if the rows 30 were strictly parallel with the warp threads.

Assuming that the heddles *A'* of the cords *A* are leveled, it will be apparent that upon either expanding or contracting the 35 comber board the heddles would cease to be level but would arrange themselves in an upward or downward curve (according as the comber board is expanded or contracted, respectively); this is undesirable, as the 40 warp should stand as nearly as possible in a perfect plane. I have found that if two comber boards be employed one above the other, one being adapted to be expanded as the other is contracted, and vice versa, the 45 effect of one upon adjustment to disturb the planiform arrangement of the heddles may be offset by reversely adjusting the other. Thus, referring to Fig. 6, if the rod *b* of the lower comber board upon adjustment to the 50 dotted line position would effect the elevation of the heddle *A'* to the dotted line position, the adjustment of the rod *b* of the upper comber board in the direction of the arrow in Fig. 6 (reversely to the adjustment of the rod *b* of the lower comber board) would accomplish depression of the 55 heddle *A'*.

Having thus fully described my invention, what I claim as new and desire to secure by 60 Letters Patent is:—

1. In combination, a supporting structure, two crossed groups of parallel spaced rods arranged in said structure and together

forming guiding holes for the harness cords, and means to alter the spacing of one group 65 of said rods including a movable system of wedge-shaped spaces interposed between the several rods of said group.

2. In combination, a supporting structure, two crossed groups of parallel spaced rods 70 arranged in said structure and together forming guiding holes for the harness cords, and means to alter the spacing of one group of said rods including a movable system of wedge-shaped spacers interposed between 75 the several rods of said group, the several spacers being movable into variously spaced relation to each other.

3. In combination, a supporting structure, two crossed groups of parallel spaced rods 80 arranged in said structure and together forming guiding holes for the harness cords, and means to alter the spacing of one group of said rods including a movable bar and a system of wedge-shaped spacers movable 85 individually on and lengthwise of said bar and interposed between the rods of said group.

4. In combination, a supporting structure, two horizontal crossed groups of parallel spaced rods arranged in said structure and together forming guiding holes for the harness cords, and means to alter the spacing of one group of said rods including a substantially horizontal bar, a system of wedge-shaped spacers movable individually on and lengthwise of said bar and interposed between the rods of said group, and means to 90 adjust the bar to different elevations in said structure.

5. In combination, a frame having spaced parallel sides and an inwardly facing groove in each of said sides, a group of parallel spaced rods having their ends received in said grooves, another group of parallel 105 spaced rods crossing the first group and forming therewith guiding holes for the harness cords, the first group of rods being movable longitudinally of said grooves, and adjustable means to confine said first rod group against movement longitudinally of 110 said grooves.

6. In combination, a supporting structure, two crossed groups of parallel spaced rods arranged in said structure and together 115 forming guiding holes for the harness cords, and means to adjust all the rods of one group into and out of right angular disposition to the rods of the other group.

In testimony whereof I affix my signature 120 in presence of two witnesses.

EUGEN SECKLER.
